James & Duncan ATTORNEYS

UNITED STATES PATENT OFFICE.

GEORGE KREMENTZ, OF NEWARK, NEW JERSEY.

BUTTON-FASTENER.

SPECIFICATION forming part of Letters Patent No. 752,293, dated February 16, 1904.

Application filed September 28, 1903. Serial No. 174,869. (No model.)

To all whom it may concern:

Be it known that I, GEORGE KREMENTZ, a citizen of the United States, and a resident of Newark, in the county of Essex and State of New Jersey, have invented certain new and useful Improvements in Button-Fasteners, of which the following is a specification, taken in connection with the accompanying drawings, which form a part of the same.

This invention relates to button-fasteners such as are adapted to be connected with the shank of a button and having a piercing end to pass through the fabric and serving to securely fasten the button thereto, while allowing for the ready removal of the same.

In the accompanying drawings, in which the same reference-numerals refer to similar parts in the several figures, Figure 1 indicates one embodiment of this invention as being inserted through the fabric. Fig. 2 is an enlarged detail of the same, partly in section. Fig. 3 is a transverse sectional view of the same, taken substantially on the line 3-3 of Fig. 2. Fig. 4 shows a modified construction of fastener as applied to a fabric.

In the embodiment of the invention shown in the drawings the fastener is shown as comprising the arms 3, of wire, which engage the shank 2 of the button 1. These arms are secured together at their forward portions to form a piercing end. The forward portions of the arms may be detachably connected by the enlarged piercing-head 4, which is indicated as formed with a threaded hole 7, so as to screw upon the threaded ends 19 of the arms. This head is indicated as having the sharp point 5 and is preferably provided with the hole 6, by which it may be rotated to detach it from the arms. The arms, which are preferably formed of resilient material, are indicated as provided with the bends 8, by which a suitable shank-retaining notch 10 is formed intermediate the ends of the fastener and preferably adjacent its central portion. The rear end of the fastener is preferably bent so as to form the forwardly-tapering shank-receiving loop 9, connecting with the notch 10. The button-shank can be forced from one to the other, although the arms are so close together as to prevent the accidental passage of the shank from the notch to the loop. The forward ends of the arms in front of the retaining-notch are preferably close together, so as to exclude the button-shank, and, if desired, the arms may be formed with suitable means to positively prevent the button-shank from being forced between the arms in front of the retaining-notch. A stop may be formed on one of the arms which may coöperate with a suitable recess formed in the other, so as to prevent the passage of the button-shank between the arms. In Figs. 2 and 3 the stops 11 are indicated as formed integral with the arms 3 adjacent the front of the retaining-notch, these stops coöoperating with suitable recesses 12 in the arms, so as to exclude the button-shank.

It is not necessary to form bends in both of the arms of the fastener. As indicated in Fig. 4, one of these arms 3 may be formed straight, while the other arm may be formed with suitable bends to constitute the shank-retaining notch near the middle of the fastener. The bend 14 at the rear of this notch is indicated as curved, so as to allow the ready passage of the shank 2 of the button 1 when it is forced in that direction, while the bend or stop 17 at the front side of the notch is given the sharp angular contour indicated, so as to closely coöperate with the opposite arm of the fastener and to effectually exclude the button-shank. The forward portions of the arms in front of the notch are preferably close together in this instance, and, if desired, they may be secured permanently together by solder or otherwise at any point between the notch and the piercing end. This would entirely prevent the button-shank from getting between the front portions of the arms; but it lessens the resilient action of the fastener to some extent. The front ends of the arms may be joined in any way to form a piercing end, and an enlarged piercing-head, such as 16, may be secured upon them in any desired way, this head being indicated in Fig. 4 as permanently secured to the front of the fastener-arms by being forced down upon them. The rear of the fastener is indicated as comprising the ta-

pering receiving-loop 15, communicating with the notch 18.

In using this fastener after the shank of the button has been inserted between 5 the arms may be readily applied to fabric by insertion through a buttonhole of the ordinary kind and is especially applicable for use with stud-buttons for shirts and other garments. Fig. 1 indicates the fastener as thrust 10 through the buttonhole of the fabric 13. The front end of the fastener is then grasped and pulled through, so that the button-shank engages the buttonhole, and thereupon the fastener is forced backward through the button- 15 shank until the shank engages the retaining-notch and the fastener assumes a transverse position, holding the button to the fabric, as indicated in Fig. 4. The fastener and button 20 may be readily removed from the fabric in an obvious manner.

It is desirable that fasteners of this class be certain in their operation and so constructed 25 that they cannot be operated wrongly under any conditions, and for this reason it is desirable that the button-shank be prevented from passing between the fastener-arms in front of the retaining-notch, since if this should happen in attempting to remove the fastener undesirable results would follow and the fastener 30 and garment might become injured. The fastener-arms are therefore preferably given such a configuration that the button-shank may readily pass from the receiving-loop at the rear of the fastener to the retaining-notch near 35 the center of the same, but is prevented from moving farther forward between the fastener-arms.

It is of course understood by those familiar 40 with this art that many modifications in the size, form, proportions, and numbers of parts may be made and that parts of this device 45 may be used without employing all of the same and may be used in connection with other devices without departing from the spirit of this invention or losing the advantages of the same. I do not, therefore, desire to be limited to the details of the disclosure which has been made in this case; but

What I claim as new, and what I desire to se-

cure by Letters Patent, is set forth in the appended claims.

1. In button-fasteners, a button having a shank and a fastener having arms of resilient material detachably secured to said shank, there being an enlarged piercing-head formed 55 with a hole, screwed upon the front ends of said arms, said arms forming a shank-retaining notch adjacent the middle of the fastener and a forwardly-tapering shank-receiving loop at the rear of the fastener, there being stops 60 on said arms adjacent the front of said notch said stops co-operating with recesses formed in said arms to prevent the passage of said shank between said arms ahead of said notch.

2. In button-fasteners, a button having a 65 shank and a fastener having arms of resilient material detachably secured to said shank, said arms forming a shank-retaining notch adjacent the middle of said fastener and being detachably connected at their forward ends by 70 an enlarged piercing-head.

3. In button-fasteners, a button having a shank and a fastener having resilient arms detachably connected with said shank and means to detachably connect the forward ends of said 75 arms to form a piercing end at the front of said fastener.

4. In button-fasteners, a fastener having arms of resilient wire and having an enlarged piercing-head secured to the front of said arms, 80 said arms being bent to form a forwardly-tapering loop at the rear of said fastener and a retaining-notch near the middle of the same, and a stop on said arms adjacent said notch to prevent the entrance of a button-shank between 85 said arms ahead of said notch.

5. In button-fasteners, a fastener having resilient wire arms and having an enlarged piercing-head secured to the front of said arms, said arms forming a shank-retaining 90 notch adjacent the middle of the fastener and formed with means adjacent said notch to prevent the passage of a button-shank between said arms ahead of said notch.

GEORGE KREMENTZ.
